UNITED STATES PATENT OFFICE.

ALFRED B. FOWLER, OF EXETER, NEW HAMPSHIRE.

HEEL-BURNISHING MACHINE.

SPECIFICATION forming part of Letters Patent No. 372,612, dated November 1, 1887.

Application filed March 12, 1887. Serial No. 930,583. (No model.)

To all whom it may concern:

Be it known that I, ALFRED B. FOWLER, a citizen of the United States, and a resident of Exeter, in the county of Rockingham and State of New Hampshire, have invented new and useful Improvements in Heel-Burnishing Machines, of which the following, taken in connection with the accompanying drawings, is a specification.

10 This invention relates to improvements in heel-burnishing machines, and it is carried out as follows, reference being had to the accompanying drawings, wherein—

Figure 1 represents a rear elevation of the machine. Fig. 2 represents a central vertical section of the same. Fig. 3 represents an enlarged vertical section on the line A B, shown in Fig. 2. Fig. 4 represents a vertical section on the line C D, shown in Fig. 2. Fig. 5 represents an enlarged cross-section on the line X Y, also shown in Fig. 2; and Fig. 6 represents a side elevation of the heart-shaped cam for imparting an oscillating motion to the burnisher-shaft.

25 Similar letters refer to similar parts wherever they occur on the different parts of the drawings.

a is the frame or standard of the machine, having bearings a' a' for the rotary driving-shaft b. (Shown in Figs. 1 and 2.)

30 b' b" are respectively fast and loose pulleys on the driving-shaft b, as usual. By means of belt-power applied to the pulley b' a rotary motion is imparted to shaft b.

35 b² and b⁴ are pulleys, also secured to shaft b, the former for setting in motion the mechanism by which an oscillating motion is given to the burnishing-shaft and the latter for actuating the mechanism by which a longitudinal 40 reciprocating motion is imparted to the said burnishing-shaft, as will hereinafter be described.

To the top of frame a is secured the bearing c' for the rock-shaft e, said shaft being further supported in its rear end in the forked bearing-bracket d, secured to the rear of frame a, as shown in Figs. 1, 2, and 3.

45 e is the burnishing-shaft, journaled in the respective bearings f and g, and having its rear end pivoted at k to the bracket or lever K, as shown in Fig. 2. The bearing f is free to move up and down in the forked arm F, secured to the

rock-shaft e in front of bearing c', as shown in Figs. 2 and 4, the said bearing f being provided with guide-pins f' f', projecting through slots 55 F' F' in the sides of the forked arm F, so as to keep the said bearing and forked arm connected together during the various motions of the burnishing-shaft.

F" is a cap-plate secured to upper end of the 60 forked arm F, and through such cap-plate is screwed the adjustable screw F³, on which is held, between nuts or collars F⁴ F⁴, the upper end of the flat spring F⁵, the lower free end of which presses on top of the bearing f, so as to 65 cause the burnisher-tool E, secured to the forward end of shaft e, to exert a proper pressure on the heel of the boot or shoe S that is being burnished. During the operation of burnishing the boot or shoe heel the boot may 70 be secured to a suitable jack, as is common in machines of this kind, or it may be held by hand, as may be desired.

The bearing g is free to move up and down in the forked arm G, secured to rock-shaft 75 e, back of the bearing c', as shown in Figs. 2 and 5, the said bearing g being provided with guide-pins g' g', projecting through slots G' G' in the sides of the forked arm G, so as to keep 80 said bearing and forked arm connected together during the motions of the burnisher-shaft.

The mechanism for imparting an oscillating motion to the burnisher-shaft is carried out as follows: To the interior of the hollow standard 85 a is secured the bearing h, in which is journaled the worm-shaft H, to which is secured the worm H'. (Shown in Figs. 2 and 4.) h' is a pulley secured to the worm-shaft H, and by means of a belt, h'', a rotary motion is 90 conveyed to the pulley h' from the small pulley b³ on the rotary driving-shaft b. The worm H' meshes into the teeth of the worm-wheel L, having shaft or spindle l, journaled in the bearing L', secured in a suitable manner within 95 the standard a, as shown in Fig. 2. To the face of the worm-wheel L is secured, in a suitable manner, the heart-shaped cam M. (Shown in Figs. 2 and 6, as well as in dotted lines in Fig. 4.) As the cam M rotates with the worm-wheel L, it actuates a pair of pins or projections, o o, on the side of the toothed rack O, and thus causes the latter to reciprocate. The 100 rack O has a downwardly-projecting guide-

piece, O' , passing freely into the slot p in the bracket or bearing-piece P , secured in a suitable manner to the inside of the hollow standard a , as shown in Figs. 2 and 4, by which arrangement the rack O is properly guided during its reciprocating motion. A set-screw, p' , and washer or plate p'' , secured to the lower end of guide-piece O' , prevents the rack O from moving out of its bearing-piece O' , as shown in said Figs. 2 and 4. The teeth of the rack O engage in segmental teeth q in the lower end of the rock-lever Q , that is pivoted on the stationary fulcrum-pin q' , secured to frame a , as shown in Figs. 2 and 4, said lever Q passing through a slot, d'' , in the top of frame a , and has in its upper end segmental teeth q'' , meshing into the toothed segment F' in the lower portion of the forked arm or lever F , as shown in Figs. 1, 2, and 4. Thus it will be seen that by this mechanism an oscillating motion is imparted to the burnisher-tool E , to cause it to follow the curvature of the heel from rear to front, the spring F^5 during such motion of the tool E causing it to follow the irregularities in the heel curvatures and to bear against the heel with a proper yielding pressure.

For the purpose of imparting a longitudinal reciprocating motion to the burnisher-shaft b , I use the following intermediate connecting mechanism: From the pulley b^4 on the driving-shaft b leads a belt, b^5 , to the pulley r , secured to the shaft R , which latter is supported in bearings $R' R''$, secured to frame a , and to said shaft R is keyed or otherwise secured the eccentric disk R'' , that is surrounded by the ring R^3 , and to the latter is secured, preferably in an adjustable manner, the rod R^4 , the upper end of which is pivoted at R^5 to the rock-lever T , as shown in Figs. 1, 2, and 3. The rock-lever T is pivoted in an adjustable manner, by means of bolt t , to the forked bracket d , and said lever T has in its upper end a fork, T' , to which is pivoted, by means of set-screws $t' t'$, the split ring k'' , located in an annular groove in the hub k^3 of the lever K , as shown in Figs. 2 and 3, said hub k^3 surrounding the rock-shaft c and preferably splined upon it, so that said hub k^3 of the lever K may be free to slide forward and back on shaft c and still partake of the rocking motion of the latter and thereby cause the burnisher-shaft e to reciprocate longitudinally and thus to impart a forward-and-back reciprocating motion to the tool E , so as to reach all parts of the heel, from top to bottom of the latter, during the operation of the machine.

For the purpose of regulating and adjusting the longitudinal reciprocation of the burnisher-shaft e , I use the following mechanism, viz: I make in the lever T a slot, T'' , in which is adjustable the bearing T^3 . (Shown in Figs. 2 and 3.) I also make slots $d' d''$ in the forked sides of the bracket d , and in said slots are adjustable the bearings $d'' d''$. (Shown in Fig. 3.) Midway upon the fulcrum pin or bolt t , I make an

enlargement, t'' , the ends of which bear against the inner flanged ends of the bearings $d'' d''$. The ends of the bolt t are screw-threaded and provided with hand-nuts $t^4 t^5$, and between such hand-nuts and the outside of the forked bracket $d d$, I locate upon the bolt t a pair of hubs or washers, $t^4 t^5$, (shown in Fig. 3;) and it will thus be seen that by loosening the hand-nuts $t^4 t^5$ the bolt t is released from the bracket $d d$, and it may now be adjusted up or down with its bearings in the slots in said bracket and lever T , according to the amount of reciprocation desired on the burnishing-tool to compensate for height of heel on the boot or shoe, and after being so adjusted the bolt t is secured firmly to the slotted bracket $d d$ by simply tightening the hand-nuts $t^4 t^5$.

E' is a gas pipe connected to the tool E for heating it, as is usual in machines of this kind; but any other or well-known means for heating the burnishing-tool may be used to equal advantage.

In the operation of the machine it will be noticed that I use three motions on the burnishing-tool—namely, a longitudinal reciprocating motion in the direction of the burnisher-shaft to cause the tool to reach all parts from the top to bottom of the heel, an oscillating motion to cause the tool to follow the curvatures of the heel from front to rear, and an in-and-out yielding motion to cause the tool to bear properly against the curved portions of the heel while the said tool is oscillated and longitudinally reciprocated.

Having thus fully described the nature, construction, and operation of my invention, I wish to secure by Letters Patent and claim—

1. In a burnishing-machine, the herein-described mechanism for imparting an oscillating motion to the burnisher-shaft, consisting of the rotary driving-shaft b , having pulley b^5 , the belt b^6 , leading from it to the pulley h' on the worm-shaft H , the worm H' , engaging with the worm-wheel L , the cam M , secured to said worm-wheel, the rack O , reciprocated by the said cam and having teeth engaging in the teeth in the lever Q , said lever being supported to rock on the fulcrum q' and having teeth in its upper end engaging in the teeth in the lower end of the forked arm F , the latter being supported on the rock-shaft c and provided with an out-and-in movable bearing, f , for the burnisher-shaft, all combined and operating substantially as set forth.

2. In a burnishing-machine, the rock-shaft c and forked arms $F G$, secured to it and having the respective movable bearings $f g$ arranged within said forked arms, and the burnisher-tool E , secured to the shaft e , in combination with the yielding spring F and the longitudinally-movable lever K , having its upper end hinged to the burnisher-shaft and its lower end or hub, k^3 , supported on the shaft c and adapted to move forward and back on the latter, as and for the purpose set forth.

3. In a burnishing-machine, the herein-de-

scribed mechanism for imparting a reciprocating motion in a longitudinal direction to the burnisher-shaft, consisting of the rotary shaft R and its eccentric R'', ring R³, and rod 5 R⁴, hinged to the rock-lever T, said lever being hung on the adjustable bolt t t'' and pivoted in its upper end to the lever K, mounted on the rock-shaft c and pivoted in its upper end to the burnisher-shaft e, all combined and to operating substantially as and for the purpose set forth.

4. In a burnishing-machine, the herein-described mechanism for adjusting the longitudinal reciprocation of the burnisher-shaft, consisting of the slotted rock-lever T and slotted forked bracket d d, the fulcrum-bolt t t t'', having bearings d'' d'' T³, clamping-nuts t³ t³, and 15 collars or washers t⁴ t⁴, all arranged and combined as set forth.

5. In a burnishing-machine, the rock-shaft 20 c and the forked arms F G, secured thereon, the movable bearings f g, arranged respectively in said forked arms, the burnisher-shaft e, journaled in said bearings f g, and the lever K, hinged in its upper end to the burnisher-shaft and having its lower end or hub mounted on and adapted to slide on the rock-shaft c, 25 all combined and operating substantially as and for the purpose set forth.

In testimony whereof I have signed my name 30 to this specification, in the presence of two subscribing witnesses, on this 10th day of March, A. D. 1887.
